UNITED STATES PATENT OFFICE.

AUGUST STÜRMER, OF ELBERFELD, PRUSSIA, ASSIGNOR OF TWO-THIRDS
TO ERNST FROHN, OF REMSCHEID, AND ALBERT BRINCK, OF BERLIN,
GERMANY.

METHOD OF AND APPARATUS FOR MAKING ANATOMICAL LASTS.

SPECIFICATION forming part of Letters Patent No. 290,652, dated December 18, 1883.

Application filed May 21, 1883. (No model.)

To all whom it may concern:

Be it known that I, AUGUST STÜRMER, of Elberfeld, Prussia, in the Empire of Germany, have invented certain new and useful Improvements in Method of and Apparatus for Making Anatomical Lasts, of which the following is a specification.

This invention has reference to an improved method of and apparatus for making lasts for boots and shoes in such a manner that an exact anatomical reproduction of the foot is represented by the last, and thereby an accurate fit of the shoes or boots obtained.

The invention consists, first, in a method of making lasts, which consists, first, in placing the foot in a position as for walking; secondly, forming a plaster-of-paris mold around the same; thirdly, making a last of cast-iron by means of the mold.

20 It consists, secondly, of an apparatus for making the mold; which will be described hereinafter, and finally be pointed out in the claims.

In the accompanying drawings, Figure 1 represents a vertical longitudinal section on line *xx*, Fig. 2, of my improved apparatus for making lasts. Fig. 2 is a plan with sole-plate removed. Figs. 3 and 4 are details. Fig. 5 is a vertical transverse section of the last-forming apparatus on line *yy*, Fig. 2. Fig. 6 is a top view of the rear part of the sole-plate. Figs. 7, 8, 9, and 10 are leather portions that provide, respectively, for corns, bunions, &c., and the extra space required for the toes; and 35 Figs. 11 and 12 are respectively a side and a bottom view of the finished cast-iron last.

Similar letters of reference indicate corresponding parts.

For making my improved lasts an apparatus is used by which an exact plaster-of-paris mold of the form and configuration of the foot is obtained. This apparatus consists of a horizontal supporting-stand, A, on which is supported a metallic sole-plate, B, which is attached thereto at its front part by means of screws *a b c*. This sole-plate B is made large enough that a sufficient space is formed around even the largest foot. By means of the foremost fastening-screw, *c*, the sole-plate can be attached either flat to the supporting-frame A, or a slight upward curve can be imparted

thereto, as shown in Fig. 1. For this purpose the screw *c* is inserted through a perforation of the sole-plate into threaded screw-holes *c'* of the supporting-stand A.

At the rear part of the supporting-stand A are arranged two vertically-adjustable screw-posts, E E', and an intermediate heel screw-post, F. These screw-posts are adjusted in nuts, *e*, *e'*, and *f*, which are guided by side 60 grooves in tongues of longitudinal recesses of the stand A; the heel screw-post F by a pin, *f'*, at its upper end through one of the heel pin-holes, *o o' o''*, &c., of the sole-plate B. The upper ends of the screw-posts E E' of the 65 sole-supporting plate B are provided with circumferentially-grooved disks *e''*, (shown in Fig. 4,) which support the sole-plate B without interfering with the adjustment of the screw-posts.

About midway between the ends of the sole-plate B is arranged a horizontal plate, T, which is swiveled to the upper end of a vertical screw-post M, that is vertically adjusted in a longitudinally-sliding nut, *m*, of frame A. 70 This transverse plate T is beveled at its front edge and placed laterally at such an angle of inclination to the axis of the sole-plate that the latter receives a slightly-inclined position, corresponding to the natural inclination of the 80 under side of the foot. A knuckle-rail, S, is adjusted above and transversely across the sole-plate B, and supported in this position by two pins, *s s'*, shown in Fig. 5, which pass through perforations of the sole-plate B, arranged in longitudinal lines, as shown in Fig. 6. The rail S is provided with a longitudinal opening, through which a cord is passed. The sole-plate B is provided below the ball of the foot with two indicator-pins, *m' m''*, which, together with the heel-pin *f'* and the knuckle-rail S, form the guides for the proper adjustment of the foot.

For making the mold the following operation is necessary: First, the supporting screw-posts E, E', and F are first set so as to correspond exactly to the length of the foot. The proper height of the heel is then determined by vertically adjusting the screw-posts E, E', and F, so that the sole-plate assumes a corresponding position. This may be facilitated by means of a scale cut into the heel screw-

post F. The transverse plate T is next adjusted by the screw-post M, so as to impart to the sole-plate the proper laterally-inclined position. The front end of the sole-plate is 5 next adjusted by the screw c to the rise of the toes. The indicator-pins m', m^2 are next inserted into the sole-plate B, and the knuckle-rail S adjusted so as to be in line with a vertical plane passing through the knuckles. The foot 10 is now covered by an elastic stocking, which is drawn over the common stocking. This elastic stocking is covered at the points where the foot was heretofore exposed to pressure by layers of leather having beveled edges, as 15 shown in Figs. 7 and 8, the shapes and sizes of which are adapted to different irregularities of the foot, according as corns, bunions, &c., have to be provided for. The space required for the toes is obtained by the toe-support 20 shown in Fig. 9, which is placed in position over the toes, while a second smaller support (shown in Fig. 10) is placed in position over the largest toe. A layer of plaster-of-paris is now spread over the sole-plate, that 25 corresponds in thickness to the height of the indicator-pins m', m^2 , and f' , and the rail S. The foot is next placed in position so as to touch lightly on the pins m', m^2 , and f' . The cord that passes through the rail S is now 30 drawn up past the knuckles and secured to the leg. The entire foot is now encased by a layer of plaster-of-paris. Before the same entirely hardens it is cut at opposite sides by means of the cord, while the mass on the sole- 35 plate is divided into two parts by the knuckle-rail. The foot is next moved away from the sole-plate, whereby the mold can be removed from the foot, the heel-section being first removed, and then the front section, and, lastly, 40 the elastic stocking drawn off. The separating-rail S is next removed from between the two mold-sections, which are then united again on the sole-plate, the indicator-pins m', m^2 and the heel-pin f' serving for replacing them into 45 proper position. The mold-sections are then reunited into one mold by plaster-of-paris. The interior of the mold is next coated in the usual manner with oil or pulverized charcoal, and the interior space filled with a mixture of 50 brick and plaster-of-paris. From the solid form thus obtained the instep is sawed off by a thin saw-blade, both forms serving as for the production of a cast-iron last. Into the sole of the cast-iron last holes are drilled, into 55 which wooden pegs are inserted, as shown in Figs. 11 and 12, which serve to attach the insole.

The cast-iron last so obtained is an accu-

rate reproduction of the shape of the foot, with all peculiarities, and in the position that 60 is assumed in walking, so that boots and shoes made on the last fit without the least pressure, and in comfortable and anatomical manner to the foot.

The right to file a separate application for 65 the last itself is herewith reserved.

Having thus described my invention, I claim as new and desire to secure by Letters Patent—

1. The method herein described of making anatomical lasts, which consists in first drawing an elastic covering-stocking over the foot; 70 secondly, placing the foot in a position as in walking; thirdly, providing for irregular and exposed parts by applying raised portions; fourthly, making a plaster-of-paris mold of 75 the foot, and, lastly, producing from the same a solid cast-iron last, substantially as set forth.

2. An apparatus for making anatomical lasts, which consists of a supporting-stand, A, 80 having vertically and longitudinally adjustable screw-posts E, E', and F, sole-plate B, adjustable transverse plate T, and adjustable separating-rail S, substantially as set forth.

3. An apparatus for making anatomical 85 lasts, which consists of a longitudinally-recessed supporting-stand, A, a sheet-metal sole-plate B, vertically and longitudinally adjustable screw-posts E, E', and F, transverse plate T, knuckle-rail S, indicator-pins m', m^2 , and 90 adjusting front screw c, substantially as set forth.

4. The combination of the elastic sole-plate 95 B, having longitudinal lines of perforations, with a transverse separating knuckle-rail, S, having pins s', s'' , said separating-rail having a longitudinal hole, and a mold-cutting cord passing through said hole, substantially as set forth.

5. The combination of the supporting-stand 100 A, having longitudinal guide-recesses, screw-posts E, E', having grooved disks e^2 , screw-post F, having a heel-pin, f' , adjustable screw-nuts e, e' , and f , sole-plate B, having longitudinal lines of perforations, and a separating 105 knuckle-rail, S, having connecting-pins s', s'' , all substantially as and for the purpose set forth.

In testimony that I claim the foregoing as my invention I have signed my name in presence 110 of two subscribing witnesses.

AUGUST STÜRMER.
